[57] **CLAIM**

The ornamental design for combined portable data processing device handle and built-in laser bar code reader, as shown and described.

DESCRIPTION

FIG. 1 is a top, left, rear perspective view of a combined portable data processing device handle and built-in laser bar code reader, on an enlarged scale;
FIG. 2 is a top plan view thereof;
FIG. 3 is a right side view thereof;
FIG. 4 is a front view thereof;
FIG. 5 is a left view thereof;
FIG. 6 is a rear view thereof;
FIG. 7 is a bottom plan view thereof; and,
FIG. 8 is a left side view thereof, on a reduced scale, the broken line drawing of a portable data processing device is shown for illustrative purposes only and forms no part of the claimed design.
